UNITED STATES PATENT OFFICE.

WILLIAM H. POWERS, OF EUGENE, OREGON.

SHOE-SHINING MACHINE.

1,391,076.

Specification of Letters Patent. Patented Sept. 20, 1921.

Application filed June 23, 1920. Serial No. 391,041.

To all whom it may concern:

Be it known that I, WILLIAM H. POWERS, a citizen of the United States, residing at Eugene, in the county of Lane and State 5 of Oregon, have invented a new and useful Shoe-Shining Machine, of which the following is a specification.

My invention relates to improvements in shoe shining machines in which a rotary brush at the end of a flexible shaft is driven by a portable electric motor.

The objects of my invention are:

First to produce a machine which will polish shoes mechanically.

Second to produce an apparatus which can be carried conveniently from place to place, quickly connected to any electric circuit, and contains all the paraphernalia required for the practice of the shoe shining 20 trade.

I attain these objects with the mechanism illustrated in the accompanying drawing, in which—

Figure I is a perspective view of the entire tire box with shaft and brush attached ready for operation.

Fig. II is a vertical, longitudinal section through the box, exhibiting the motor within the box.

Fig. III is a section through Fig. II along the line A—A, also illustrating constructive details of the flexible shaft.

Fig. IV is a perspective view of the end of the flexible shaft.

Similar numerals refer to similar parts throughout the several views.

The electric motor 1 is placed in a box 2 having a hinged lid 3 and a handle 4 on the lid for convenient transportation. The 40 terminals 5 for the motor are located outside the box, and so is the rheostat 6. For convenience of illustration the connecting wires between terminals, rheostat and motor are shown exposed, in actual practice these 45 wires should be protected from damage by being embedded in the walls of the box.

Attached to the motor shaft by means of suitable couplings 7, is the flexible tube 8, and within the tube the flexible shaft 9, the 50 latter essentially composed of a chain which is rotatably confined within the tube. Attached to the other end of the chain is a solid axle 10 having a collar 11 which rests against the end of the flexible tube. The

rotary brush 12 is slipped on the axle and 55 compelled by the key 13 to rotate with the shaft. The handle 14 permits a convenient manipulation of the brush. A small plate 15, pivoted eccentrically to the end of the axle, will during rotation be thrown over 60 the core of the brush, and prevent the latter from flying off the axle. When the motor is stopped by the manipulation of the rheostat the plate 15 can readily be switched from the core on to the end of the axle, 65 and the brush can be quickly removed and replaced by another brush.

When ready to be moved to some other location, the box is disconnected from the electric circuit, the couplings on the motor 70 shaft are uncoupled, the shaft is coiled up and placed with the brushes and other paraphernalia into the box, and everything is ready for moving.

Having thus described my invention, it 75 will be seen that my objects have been accomplished and, although I have shown the preferred form of construction, I reserve to myself the right to make minor changes, providing I do not violate the spirit and 80 principle of my invention; especially may the electric motor be replaced by a water motor, in which case, of course, the rheostat and terminals may be omitted. The rest of the structure requires no material change. 85

I claim:

1. In a shoe shining machine, the combination of the flexible shaft, and a rotary brush, with a solid shaft attached to the end of the flexible shaft and entering the 90 hub of the rotary brush, an end plate pivoted eccentrically to the end of the solid shaft, said end plate being swung by centrifugal force over the hub of the rotary brush to hold the rotary brush on the solid 95 shaft.

2. In a shoe shining machine, a solid shaft having one end adapted to be attached to a flexible shaft, an end plate pivoted eccentrically to the other end of said 100 solid shaft, the greatest length of said end plate not to exceed the diameter of the solid shaft, a collar intermediate the two ends, and a key longitudinally with the solid shaft from the collar to the end plate. 105

Signed by me at Eugene, Oregon, this 16th day of June, 1920.

WILLIAM H. POWERS.
